C. S. APPLAS.
VEHICLE CURTAIN.
APPLICATION FILED OCT. 31, 1913.

1,110,857.

Patented Sept. 15, 1914.

UNITED STATES PATENT OFFICE.

CLARENCE S. APPLAS, OF MOLINE, ILLINOIS.

VEHICLE-CURTAIN.

1,110,857.

Specification of Letters Patent. Patented Sept. 15, 1914.

Application filed October 31, 1913. Serial No. 798,513.

To all whom it may concern:

Be it known that I, CLARENCE S. APPLAS, a citizen of the United States, and a resident of Moline, in the county of Rock Island and State of Illinois, have made certain new and useful Improvements in Vehicle-Curtains, of which the following is a specification.

This invention relates to vehicle curtains, and one of the principal objects thereof is to provide an improved manner of arrangement of automobile or other vehicle curtains including a manner and means of convenient and easy stowage of the curtains when the same are not in use, and means for quickly and easily swinging the curtains into position for service, and means for holding them in that position.

With these and other objects in view, which will become apparent as the description proceeds, the invention resides in the construction, combination and arrangement of parts hereinafter more fully described and claimed, and illustrated in the accompanying drawing in which like characters of reference indicate like parts throughout the figures, of which,

Figure 1 represents a fragmental perspective view of the inside of a vehicle top illustrating the manner in which the curtains are positioned for use. Fig. 2 represents a fragmental perspective view of a bow, showing a curtain in stowed position thereon, and Fig. 3 represents a fragmental front elevational view of a bow, showing a curtain secured thereto ready to be rolled up for stowage.

Referring more particularly to the drawing, 5 illustrates the forward central, 6 the rear central and 7 the rear bow, respectively of an automobile or other vehicle top, and 8 the material ordinarily secured thereto, for forming the top.

To the curvature of each bow on the inside thereof is pivoted, by means of a screw eye 9, one end of an arm 10, the opposite end of which is looped at 11 through a metallic eye 12 secured in the rear upper corner of a side curtain 13, said curtain provided adjacent said eye and below the same with a second eye 14 for engagement over a turn button 15 when the curtain is in position for service, as illustrated in Fig. 1.

A spring hook 16 formed of wire or other suitable material is secured to each bow on

the inside thereof and below screw eye 9 in such position that when the curtains are down in position for use, the arms 10 may be engaged near their lower ends in said hooks for securely holding the upper rear corner of the curtains against the bow. As shown, the lower ends of the arms are bent as at 20 so as to bring the upper edges of the curtains flat against the sides of the bows. 65

The buttons 15 on the forward central and rear central bows of the top, engage the rear portions of the front curtain A and the central curtain B respectively, and the turn button on the front central bow is also engaged through an eye 17 near the front edge of the central curtain B while the button on the rear central bow 6 similarly engages the front portion of the rear curtain C, the turn button on the rear bow 7 engaging the 75 rear portion of last said curtain.

An arm 10 is secured to each of the designated bows, so that a curtain may be stowed on each of the three rear bows of the top, by means of straps 18 secured to the bows 20 beneath the top in such position that when the curtains are swung transversely of the vehicle top, the arms 10 having been disengaged from hooks 16, the curtains may be rolled up and secured by means of the 25 straps to the under side of the bows as illustrated in Fig. 2. In order to secure the curtains transversely of the carriage top previously to rolling said curtains, a turn button 19 is secured to the under side of 30 each bow adjacent the farthest strap from the arm 10, said button adapted to engage the eye 17, in the forward part of the curtain, connected to that bow, as illustrated in Fig. 3, whereupon the curtain may 35 be rolled up and stowed as described. By this construction it will be apparent that when the curtains are in position for service, the top edges thereof are securely held in 40 position against the inside of the bows, in 45 such a way that they could not be disturbed by strong wind or by vibration of the vehicle from any cause, and that when not in use, the curtains may be quickly and conveniently stowed in an out of the way 50 position.

Although I have described the preferred embodiment of my invention, I may desire to make such changes in the construction, combination and arrangement of parts 110

thereof, as do not depart from the spirit of the invention, and the scope of the appended claims.

Having thus fully described my invention, 5 what I claim as new and desire to secure by Letters Patent is:—

1. The combination with a vehicle top providing a bow, of a screw eye secured to the inside curvature of the bow, an arm pivotally connected at one end to said screw eye and having a loop at its opposite end, a curtain having an eye in one corner in which said loop is engaged, a hook on the inside of the bow below the curvature to engage 10 said arm when the curtain is in position for use, a turn button on said bow for holding the curtain against the bow below the hook, a pair of straps secured to the bow for holding the curtain to the underside 15 thereof when the curtain has been rolled up for stowage and a turn button on the underside of the bow adjacent one of the straps, for holding the curtain previously to rolling the same.
2. In a vehicle top including a bow, an arm pivoted at one end to the curvature of the bow, a curtain carried by the arm, means carried by the bow adapted to engage the arm when in one position for holding the 20 curtain in operative position, and means 25
- 30

carried by the bow adapted to engage the curtain when in inoperative position.

3. The combination with a bow, of an arm connected therewith, a curtain connected to said arm, means below the connecting point 35 of the bow and arm for engaging said arm and holding the same and consequently said curtain against the bow when the curtain is in position for use, and means for stowing said curtain when the same is not in use. 40

4. The combination with a bow, of an arm pivoted to the curvature thereof, a curtain connected to one end of said arm, said arm adjacent last said end being bent to lie flat against the bow when the curtain is in position for service, and means for engaging said arm to hold the same against said bow when the curtain is in position for service. 45

5. In a vehicle top, the combination with a bow of a curtain carrying bracket swinging between position for stowing the curtain and position for using the same, and means for engaging said bracket to hold the same against said bow when in last said position, for maintaining the curtain against 50 the bow. 55
